UNITED STATES PATENT OFFICE.

MATTHEW M. MERRITT, OF MIDDLETON, MASSACHUSETTS, ASSIGNEE, BY MESNE ASSIGNMENTS, TO GENERAL ELECTRIC COMPANY, A CORPORATION OF NEW YORK.

FILAMENT-SUPPORT.

1,160,745.

Specification of Letters Patent. Patented Nov. 16, 1915.

Application filed July 18, 1910. Serial No. 572,418.

To all whom it may concern:

Be it known that I, MATTHEW M. MERRITT, a citizen of the United States, and a resident of Middleton, county of Essex, State of Massachusetts, have invented an Improvement in Filament-Supports, of which the following description, in connection with the accompanying drawings, is a specification, like letters on the drawings representing

like parts.

This invention relates to lamps, being more particularly concerned with means for providing an improved form of support for a lamp filament, especially filaments which are fragile and easily broken such, for example, as those made of tungsten.

The invention will be best understood by reference to the following description when taken in connection with the accompanying illustration of one specific embodiment thereof, while its scope will be more particularly pointed out in the appended claims.

In the drawings: Figure 1 is an elevation partly in section showing an incandescent lamp having a tungsten filament and provided with a filament support embodying one form of the invention. Fig. 2 is an end view of the lamp stem with the filament and supports attached thereto; and Fig. 3 is a view similar to Fig. 1 showing a modified form of the invention.

Referring to the drawings and to the embodiment of the invention shown in Fig. 1, there is illustrated an ordinary form of incandescent lamp having the bulb 1 provided with the usual threaded base 2 and the stem 3. The hollow portion of the stem 3, through which pass the lead wires 4 and 5 instead of terminating, as usual, a short distance from the base of the lamp, is prolonged so that the sealed portion 6 of the stem, through which the lead wires emerge into the vacuum space of the lamp, is brought well forward into the lamp space and well down toward the opposite end of the filament. The current, therefore, instead of being brought into the lamp space near the base end of the stem, is brought into the same near the opposite end of the stem. At the sealed stem portion 6 the lead wires are electrically connected to the conductor-supports 7 and 8, respectively, which are bent back to have a generally parallel relation with the stem, being provided at

55 their opposite ends with suitable joints or

connections 9 and 10 to which the terminal ends of the filament are secured. This provides for each terminal end of the filament a flexible wire support having its opposite end anchored or fixed to the stem but the filament-attached end free of connection thereto. The supporting wires 7 and 8, extending as they do for some distance substantially parallel with the stem from their point of attachment thereto, provide a flexible support for the ends of the filament which is vibratable transversely the length of the filament and readily absorbs the ordinary shocks and vibrations which the latter is apt to receive. The filament appearing, as is usual, in the form of a series of horseshoe loops or sectional lengths, is also supported at intervals intermediate the conductor supports 7 and 8 by other vibratable supports in the form of supporting members parallel with or extending in the same general direction as the stem and connected each to the stem or other fixed part of the lamp only at that end opposite the end to which the filament is attached. While each section of the filament both at the base end and the opposite end of the lamp might be so supported; or the filament might be so supported only at the opposite or tip end of the lamp, herein such flexible supports are provided for the sectional lengths of filament only at the base end of the lamp, there being provided for that purpose a series (herein three) supporting wires 12 which are fixedly secured at one end to a prolongation 13 of the stem, but extend back toward the base of the lamp so as to present each at its opposite end a flexible support for the filament at that point.

While the filament might be continuous without interruption and looped or hung merely over the end of the support 12, herein in the latter is provided with short electrically connected metallic arms 14 to each of which an end of a filament length is connected. It is to be understood that the specific kind of connection which the filament has with its supports, as well as the shape or general arrangement of the filament, is immaterial, the purpose of my invention being to afford a flexible support for the filament adapted to protect the latter from shocks or jars.

If desired, both ends of each branch or length of the filament might be flexibly sup-

ported in the manner described, but herein in the lower or opposite portions of the filament are supported by being looped over short anchor wires 15, the latter being connected to the prolongation 13 of the stem.

The flexible supports 12 are preferably formed of metallic wire, such as copper wire, although they may be constructed of glass or other suitable material if desired.

10 In Fig. 3 I have shown a modified form of my invention wherein the sealed portion of the stem from which the leading-in wires emerge is located nearer the base end than the tip end of the lamp, the stem, however, 15 still providing flexible supporting devices of the same general character as those shown in the lamp just described. In this modification, as well as in the construction hereinbefore described, the lamp filament extends 20 back of the sealed portion of the stem and, therefore, back of the point of emergence of the leading-in wires. To provide the conductor supports for the ends of the filament the wires 16 and 17 which are connected to 25 the leading-in wires extend well down into the lamp and are then bent back so as to provide at 18 and 19 connections for the ends of the filament. This provides freely 30 vibratable end connections for the filament of the same general character as those first described.

The flexible supports 20 for intermediate portions of the filament are flexibly secured to the head or enlargement 21 carried by 35 prolongation 22 of the stem and a further enlargement 23 at the end of said prolongation supports the anchors 24 for the lower or opposite ends of the filament sections.

The length of the overhanging flexible 40 supports, as well as their size and stiffness may be widely varied to suit the sides of the lamp and to give the degree of flexibility which it is desired to impart to the support in any given case, but, by varying 45 these dimensions, any desired degree of flexibility may be imparted to the support in a direction transverse to the general length of the filament and the shocks or jars otherwise reaching the filament will be absorbed in the support.

By extending the hollow portion of the 50 stem well into the lamp, as shown in Fig. 1, the large diameter of the stem may be usefully employed for presenting a suitable reflecting surface, or may be used to display a label or other designating or identifying marks where they will be clearly discernible.

While I have herein shown and described

for the purpose of illustration one specific form of the invention, it is to be understood 60 that the same is not limited to the specific constructional details disclosed, but that wide deviations may be made therefrom without departing from the spirit of the invention.

65

Claims:

1. An incandescent lamp having a stem prolonged into the lamp from the base end thereof, leading-in wires emerging from the stem relatively nearer the tip end of the 70 lamp than the base end, and a plurality of flexible filament supports held at one end by and extending in the same general direction with the stem.

2. An incandescent lamp having a glass 75 stem extending therethrough from the base end to a point adjacent to the tip end thereof, leading-in wires extending through the said stem, a filament in said lamp and support wires therefor electrically connected to 80 the said leading-in wires at one end and at the other end to the said filament and extending longitudinally of the said stem.

3. An incandescent lamp having a glass 85 stem extending therethrough from the base end to a point adjacent to the tip end thereof, leading-in wires extending through the said stem, a filament in the said lamp, and support wires for the said filament attached to the tip end of the said stem and electrically connected to the said leading-in wires, 90 the said support wires extending longitudinally of the said stem and being attached to the said filament near the base end of the said lamp.

4. An incandescent lamp having a stem extending from the base to a point adjacent to the tip of said lamp, leading-in wires emerging from an intermediate point in said stem, a filament composed of a plurality of lengths extending back of said point of emergence, and flexible conducting and supporting members for the said filament electrically connected to said leading-in wires and supported by the said stem at 100 105 said point of emergence extending back toward the base of the said lamp and electrically connected to the said filament.

In testimony whereof, I have signed my name to this specification, in the presence 110 of two subscribing witnesses.

MATTHEW M. MERRITT.
